United States Patent Office

Des. 213,071
Patented Dec. 31, 1968

213,071

ANCHOR INSERT

Martin William Boll, East Rockaway, and Robert Murray MacRobbie, Seaford, N.Y., assignors to Richmond Screw Anchor Co., division of Shattuck Denn Mining Co., Bronx, N.Y.

Filed Apr. 30, 1968, Ser. No. 11,715

Term of patent 14 years

(Cl. D54—9)

FIG. 1

FIG. 2

FIG. 3

FIG. 4

FIG. 5

FIG. 6

FIG. 1 is a side elevational view of an anchor insert embodying our design;

FIG. 2 is a left end elevational view thereof;

FIG. 3 is a right end elevational view of said anchor insert;

FIG. 4 is a side elevational view of modified form of another embodiment of said anchor insert;

FIG. 5 is a left end view of the form shown in FIG. 4; and

FIG. 6 is a right end view of FIG. 4.

We claim:

The ornamental design for an anchor insert, substantially as shown and described.
